N. V. SMITH.
DISINFECTING DEVICE FOR TELEPHONE AND OTHER USES.
APPLICATION FILED OCT. 23, 1920.
1,386,975. Patented Aug. 9, 1921.

Inventor:
Northev V. Smith
by Geo. N. Goddard, atty.

UNITED STATES PATENT OFFICE.

NORTHEY V. SMITH, OF BOSTON, MASSACHUSETTS, ASSIGNOR TO GEORGE A. GOULSTON, OF BOSTON, MASSACHUSETTS.

DISINFECTION DEVICE FOR TELEPHONE AND OTHER USES.

1,386,975.

Specification of Letters Patent.

Patented Aug. 9, 1921.

Application filed October 23, 1920. Serial No. 418,990.

To all whom it may concern:

Be it known that I, NORTHEY VAUGHAN SMITH, a British subject, and resident of Boston, in the county of Suffolk and State 5 of Massachusetts, have invented certain new and useful Improvements in Disinfecting Devices for Telephone and other Uses, of which the following is a specification.

The present invention is intended to provide 10 a device for disinfecting and deodorizing mouth pieces of telephone transmitters to keep the same sterilized and thus prevent the transmission of disease germs through telephones which are a prolific source of 15 communicating disease.

Heretofore it has been proposed to insert 20 in the mouth piece some sterilizing agent or preventive but these are objectionable to users as tending to obstruct or impair the efficiency of the telephone service, whereas the 25 present device is based on the principle of leaving the mouth piece entirely free or unobstructed while suspending a disinfective pad outside of the mouth piece but in close enough proximity thereto to allow the fumes 30 therefrom to penetrate the mouth piece and keep the same sterile. A further feature consists in the particular construction by which old pads may be conveniently replaced by fresh ones as often as need be.

These and other features of the invention will be described in the following specification and will be defined in the claims hereto annexed.

In the accompanying drawings I have 35 illustrated a simple and convenient form embodying the principles of this invention, in which—

Figure 1 is a front elevation showing the 40 disinfecting pad operatively suspended from the telephone transmitter.

Fig. 2 is a side elevation of the same.

Fig. 3 is a front view of the complete device ready for attachment.

Fig. 4 is a vertical central section showing the back and front holding members with the disinfecting pad interposed between them.

According to the practice of the invention according to the form illustrated in the 50 drawings I provide a pad suspending member comprising a back piece 2 of any suit-

able thin sheet material such as prepared cloth, leather, paper, metal or the like whose lower pendant portion forms a backing for the sterilizing pad made in disk form and whose upper portion is formed with an orifice at 3 of suitable size to pass around or receive the exterior of the rear end of the telephone mouth piece 1, preferably the reduced end 10 thereof whereby the shoulder 55 11 serves to pinch the suspending portion of the back against the transmitter 12.

Suitable retaining means are provided for protecting and holding the pad in place. As shown in the drawings this comprises a front 60 member 4 preferably of like material to that forming the back and this front member is perforated as shown at 5 to allow the fumes to rise into the mouth piece. The upper end 65 of the front member may, as shown, extend 70 upward to form a suspension portion 6 which like the back member is perforated to pass over the inner end of the mouth piece.

Where pliable material like rubber or cloth 75 is used for the pad container or carrier the two members thereof may be stitched together near their outer edges as indicated at 9, a sufficiently wide unstitched place being left above the pad receiving portion to allow 80 the two members to be opened apart to admit the pad or to remove it for purposes of renewal.

It will be found that although the sterilizing 85 pad is not directly in the mouth piece yet when suspended behind the front thereof the fumes will readily penetrate the open front and will be effective in destroying germs and deodorizing the mouth piece. There is a material advantage in providing both pad retaining members with a suspension tab perforated to fit over the reduced end of the mouth piece because with that form of construction the opening through which the pad is inserted is tightly closed thereby preventing the edges at the opening from gaping 90 open to catch dust or other foreign particles.

While I have shown stitching for holding the two retaining members together it will be understood that any suitable connecting means may be employed.

What I claim is:

A disinfecting device for telephones em-

bracing front and back members stitched together around their lower edges and having upwardly extending perforated suspension tabs capable of being separated to admit a 5 pad, the front member being perforated to allow the escape of fumes into the mouth piece, and a disinfecting pad inserted be-

tween the two members opposite the perforation in the front member, substantially as described.

10

In witness whereof, I have subscribed the above specification.

NORTHEY V. SMITH.
